UNITED STATES PATENT OFFICE

BENJAMIN C. WEBSTER, OF SOUTHPORT, CONNECTICUT, ASSIGNOR TO THE BRYANT ELECTRIC COMPANY, OF BRIDGEPORT, CONNECTICUT, A CORPORATION OF CONNECTICUT

ATTACHMENT PLUG WITH PILOT LIGHT

Application filed January 8, 1930. Serial No. 419,337.

This invention deals with the construction of an electrical fitting in which are combined a flush receptacle for an attachment plug and a pilot light. The two parts are so related 5 that whenever the prongs of a plug are put in to engage the receptacle contacts, a circuit is completed through the lamp so that there may be an indication that the attachment is receiving current. Such a fitting is 10 a known thing. The aim of this invention is to make its construction simpler and less expensive.

In the accompanying drawing,

15 Figure 1 is a side view in elevation of a fitting made to embody this invention, a part being broken away about on the section line 1—1 of Figure 2.

20 Figure 2 is a view of the back of the face plate for such a fitting.

25 Figure 3 is a view looking into the base part of the said fitting.

Figure 4 is a view in section through the 30 said base on the line 4—4 of Figure 3.

Figure 5 is a view in section through the 35 fitting on the line 5—5 of Figure 1.

Figure 6 is a perspective view of the three 40 contact parts carried by the base.

The fitting is made up of a face plate 10, 45 having openings 11 for the attachment plug 30 prongs and an opening for a lens 12 held in place by two retainers 13 on the back, together with a base 14 in which are set the contact pieces, one of which carries the lamp 15. The open side of the base and a part of the 50 back of the face plate are made to fit together and by reason of the covering of the open side of the base by the face plate, the contacts set in the former are held in place, the receptacle contacts being thereby put in register 55 with the prong openings 11 and the lamp 14 in register with the lens 12.

The base is a piece of insulating material 60 molded to shape. It is open at one side and the rim 16 at this side is faced off in a single 65 plane except along one edge where there is a portion 17 slightly set back. By reason of this, the open side rests against the flat rear side of the face plate within a bead 18 on the latter. This bead, being of a size and shape 70 to conform to the outline of the rim 16 (or

in other words to the lower portion of the base), serves to position the base. Thus the base may be fitted within the bead and when the device is assembled the bead will appear as a molding around the lower part of the 55 base. The part of the plate outside of the bead may be thinner than that within, though reinforcing ribs of thicker section are desirable. The part 17 that is slightly set back overlies that part 19 of the positioning bead that forms one edge of the hole for the lens 12. From this part 19 of the bead extend two rivet posts 20 which are embedded at one end in the face plate and which extend through holes 21 in the base so that when 60 spun over at their outer ends they hold the base against the face plate. The two lens retainers 13 have holes enabling them to be set over these posts to rest between the base and the face plate, and as they extend over the ends of the lens 12, they hold the flange 22 of the latter firmly against a recessed ledge 23 around the lens opening.

At the end toward the lens, the base has a flared opening 25 leading to a central well 75 26 to permit the contact end of the lamp 15 to extend into the base for support while having its globe in register with the lens. At either side of the central well 26 are two bays 27, 28 which open through opposite walls of the base, and another bay 29 extends from the central well to the end wall opposite the lamp opening. The edges of the base wall where the bays 27 and 28 open to 80 the outside are beveled.

One wall of the bay 27 has a groove 30 receiving one edge of a plate 31 of rigid metal 85 which carries a screw 32, thus forming a binding post accessible from outside the base. A 90 rib on the floor of the bay braces the plate 31 on the inside. An integral extension 33 at right angles to this plate rests against the other wall of the bay and a further integral extension 34 at right angles to the one just mentioned lies along one side wall of the bay 29. This unitary piece forms a combined 95 binding post and receptacle contact. The outer edges of the plate 31 and the extension 34 are substantially flush with the rim 16 of 100

the open side of the base and the said edge of the extension 34 is beveled.

In the bay 28 is a plate made up of a heavy metal part 35 secured to a part 35^a of lighter, resilient metal, and carrying a binding screw 36, accessible from the outside on the opposite side of the base from the one described above, and extending through both parts. A rib on the base of the well braces the plate 10 on the inner side and, in conjunction with the inner faces of the base against which the edges of the plate rest, gives the effect of a slot for the plate. The plate has a right angle extension 37 or lamp holder integral with 15 the heavy part 35 and this extension has a spiral loop 38 at its forward end which lies at the inner end of the lamp opening 25, thus providing a means of support for the lamp inasmuch as its spiral is of the pitch of the 20 threads on the lamp shell. Another extension 39 integral with the light metal part 35^a of the plate lies along the other wall of the bay 28 and has an integral U-shaped end portion 40 extending into the bay 29 along the 25 wall of the latter opposite from the contact extension 34. In similarity to the other unitary binding post and contact member, the outer edges of the binding post plate 35 of this member are substantially flush with the 30 rim 16 of the base, as are the outer ends of the U-shaped contact portion 40 which are flared apart to form a conventional, resilient-blade receptacle contact.

A partition 41, an integral part of the base, 35 extends through the bay 29 along side of the U-shaped contact 40 and toward the central well where it bends to one side to shield the contact 40 from the inner end of the lamp. On the other side of the lamp is a similarly 40 formed insulating partition 42 between the central well and the bay 27. The end of the latter partition 42 has a recess leaving a rib 43 and opposite this on the wall of the base is a rib 44, between which and the wall of the 45 bay 29, rests the end of the contact 34.

Sprung between the ribs 42, 43 and the partition 41 in the bay 29 is a bent over contact member 45 of thin resilient metal. One leg 46 of this member lies against the ribs 42, 43 parallel to but spaced from the contact 34. The length of this leg is such as to locate the bend 48 practically flush with the beveled end of the contact 34. The other leg 49 extends diagonally inwardly to the 50 partition 41 and at its inner end it has a narrow extension reaching into the central well where it carries a small bent-over terminal piece 50 forming the center contact for the lamp.

60 The arrangement is such that when the base is in place against the back of the face plate, the blades of the contact 40 register with one plug opening 11 to receive between them one prong of an attachment plug, and the contact 34 and the leg 46 with the bend 48 are

in register with the other opening whereby to serve as the jaws or blades receiving the other plug prong between them. It will be evident from this that the plug bridges not only the line terminals represented by the two binding posts but also the center and shell contacts of the lamp because of the connection thereby made, through the attachment, from the member 45 to the contact blades 40 and the loop 38 which is a part of 75 the same unitary member.

There is no need of rivets or other securing devices to hold the contact members in place when the fitting is assembled inasmuch as they are held from sidewise movement by the parts of the base against which they lie, and from movement out of the base by reason of the facts that the face plate covers the open side of the base and that the edges of the contact members over a considerable part of their extent are substantially flush with the rim of the base and hence are held directly by the face plate. This gives an effective construction enabling the contacts to maintain their position in spite of frequent insertions 80 of attachment plugs. The absence of separate securing devices reduces the cost both of material and of manufacture.

The assembly is a matter of no difficulty as the contact parts are readily set in place in the base and may be held from slipping out by grasping the base in such a way as to engage the binding screws with the thumb and finger. This involves no awkwardness but is a natural way of handling the base 100 while placing it against the face plate. The bent contact does not slip out as it is made of resilient metal and is sprung into place. The other members are made mainly of thicker stock, relatively non-resilient. The restraint upon movement, imposed by the face plate, is important however in holding all three contact members against the forces exerted during the use of the fitting which tend to disturb the original setting that gives 105 most satisfactory results.

I claim—

1. In an attachment plug receptacle, a molded face plate having openings for plug contacts and a bead on the back thereof to 115 position a base, in combination with a base having an open face and recesses for contact members, means securing said base in position within the bead on said plate with its open face presented to the back of said plate, and contact members in said recesses engaging the sides thereof and having portions extending sufficiently toward said open face to engage the back of said plate whereby alone they are secured in the base.

2. In an attachment plug receptacle, a molded face plate having openings for plug contacts and a lens opening, in combination with a base having an open face and recesses for contact members, means securing said 120

base in position against the back of said plate with its open face presented thereto, contact members in said recesses engaging the sides thereof and having portions extending sufficiently toward said open face to engage the back of said plate whereby alone they are secured in the base, and a lamp holder electrically connected with one of said contacts, said base having a lamp opening at the end to-
ward the lens opening in the face plate.

3. In an attachment plug receptacle, a molded face plate having openings for plug contacts, in combination with a base having an open face and recesses for contact members, means securing said base against the back of said plate with its open face presented thereto, said face plate having a continuous bead conforming in outline to a portion of the open face of said base and being adapted to receive said portion of the base within it to position said base, and contact members engaging the sides thereof and having portions extending sufficiently toward said open face to engage the back of said plate whereby alone they are secured in said base.

4. In an attachment plug receptacle, a molded face plate having openings for plug contacts and a lens opening, in combination with a base having an open face and recesses for contact members, means securing said base in position against the back of said plate with its open face presented thereto, said face plate having a bead conforming in outline to a portion of the open face of said base and being adapted to receive said portion of the base within it to position said base, and contact members in said recesses engaging the sides thereof and having portions extending sufficiently toward said open face to engage the back of said plate whereby alone they are secured in the base, and a lamp holder electrically connected with one of said contacts, said base having a lamp opening at the end toward the lens opening.

45 5. In an attachment plug receptacle, a molded face plate having openings for plug contacts and a lens opening, in combination with a base having an open face and recesses for contact members, means securing said base in position against the back of said plate with its open face presented thereto, contact members in said recesses engaging the sides thereof and having portions extending sufficiently toward said open face to engage the back of said plate whereby alone they are secured in the base, a lamp holder electrically connected with one of said contacts and a lens in said lens opening held in position by said base, said base having a lamp opening at the end toward the lens opening.

In testimony whereof I have signed my name to this specification.
